W. D. PIERSON,
EYELET MACHINE,
APPLICATION FILED JULY 17, 1919.

1,353,493.

Patented Sept. 21, 1920.

UNITED STATES PATENT OFFICE.

WILLIAM D. PIERSON, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

EYELET-MACHINE.

1,353,493.

Specification of Letters Patent. Patented Sept. 21, 1920.

Application filed July 17, 1919. Serial No. 311,514.

To all whom it may concern:

Be it known that I, WILLIAM D. PIERSON, a citizen of the United States of America, and a resident of Waterbury, county of New Haven, and State of Connecticut, have invented certain new and useful Improvements in Eyelet-Machines, the principles of which are set forth in the following description and accompanying drawings, 10 wherein is disclosed the form of the invention which I now consider to be the best of the various forms in which said principles of the invention may be embodied.

This invention relates to improvements 15 in eyelet machines.

The object of this invention is to provide means for preventing injuries to the bumper and plunger, or either of them, by the normal operation of the machine.

20 The invention consists of the improved arrangement and construction shown in Figure 1 of the drawings, Fig. 2 being an outline illustration of the prior art.

Of the drawings Fig. 1 is a side elevation 25 of the relevant parts of an eyelet machine embodying the improvements;

Fig. 2 is a side elevation showing the most relevant parts of the prior construction;

Fig. 3 is a horizontal section on line 3—3 30 of Fig. 1 showing the improvements in assembly, and Figs. 4 to 7 are details of the improvements, Figs. 4 and 5 being a plan and an elevation of the buffer-rod or plate 36 (Fig. 1, middle) and Figs. 6 and 7 being 35 an elevation and a plan of the buffer-support 32 (Fig. 1 middle).

The type of machine to which this invention relates is clearly indicated by Fig. 1. The name "eyelet machine" was first applied to such machines nearly half a century ago because at first they were used only to make eyelets; but subsequent experience demonstrated their adaptability to an almost unlimited class of work of the nature 45 which involves the cutting of a blank from sheet metal and subsequent operations of drawing, forming, piercing, light stamping or the like. Hence nowadays eyelet machines are designed and used to make various small sheet metal articles which are finished complete by the machines without any annealing or subsequent operation whatever.

An eyelet machine is essentially a multiple press; and Fig. 1 is a side elevation of 55 the essential portion of one of such presses. A front elevation would show merely a plurality of such presses arranged side by side and all operated by cams on shaft 2. (The horizontal sectional view of Fig. 3 shows a 60 plurality of sets of the present improvements as applied to a plurality of such consecutive presses in a machine wherein the last press turns out the finished product.) Each of such presses executes its special 65 operation on the work, and any suitable carrier automatically transfers the articles in process from each press to the next. (Such a suitable carrier is shown in U. S. patent to Kahl, No. 808,758, dated January 2, 70 1906). Meanwhile all the multiple presses are being operated simultaneously via cam-shaft 2 (Fig. 1) on the articles in successive steps of the process.

As shown in Fig. 1, each press has a push-down or plunger cam 7 secured by feather 75 3 to cam-shaft 2 suitably mounted (mounting not shown) in the main frame 1 for all the presses. In the position shown in Fig. 1 this plunger cam 7 has just caused a downward plunge of all the parts shown below it save only the stationary frame 1 in which said parts are mounted to be vertically reciprocable. Near and at the end of this downward movement the punch 30 engages 80 85 the article to be shaped in die 31. In Fig. 1 plunger cam 7 is shown in its lowermost stage of operations and pressing against buffer 36 which is a novel feature.

Cam-shaft 2 rotates anti-clockwise as indicated by the arrow at the left in Fig. 1.

Fig. 2 shows all the parts necessary to be considered in order to understand the prior art, in connection with the prior art features not yet used in the new combination of 95 Fig. 1.

Mounted on shaft 2 (Figs. 1 and 2) is a lifting cam 8 (one for each press), which (on the continued operation of the machine, and the continued anti-clockwise revolution of this lifting cam 8,) engages beneath the lifting member 9 which is fixed to lifter rod 11, which is reciprocable in the two bronze bushings 14 (Fig. 1) mounted in frame 1, so that all the movable parts are lifted to 100 105 the position shown in Fig. 2 from the lower

positions shown in Fig. 1. When thus lifted the punch 30 (Fig. 1) is separated from the article in process in die 31. All cams 7 and 8 are preferably of tool steel accurately milled to shape and hardened to resist wear.

Lifter rod 11 (Fig. 1) is fixed by angle or knee 17 to the plunger 18 at the left so that all these parts reciprocate together following the action of cam shaft 2. As indicated (Fig. 2) by the contour of plunger cam 7 a downward movement of plunger 18 is produced, the increment preferably growing less per degree of cam rotation.

In Fig. 2 the point of cam 7 is about to begin to move down clockwise and in doing so imparts to the member 22^A a side-sweeping force. This member is termed the bumper head and is usually made of hardened steel. Lifter cam 8 is shaped as shown, so as not to interfere with the action of pushdown cam 7.

For many years the construction and operation has been as shown in Fig. 2. The plunger 18 is usually rectangular in horizontal cross section for convenience in machining; and at its lower end as shown in Fig. 1 said plunger carries the punch 30. Plunger 18 (Fig. 2) is formed with a circular hole 26 which receives bumper shank 20 the upper end or head 22^A of which has existed as a diametrically square mushroom head extending beyond hole 26 entirely around it above a part 29^A (Fig. 2) formed on the upper end of plunger 18. As shown in Fig. 2 where bumper-head 22^A is shown in side elevation, the top of end surface of said head has a curvature (from left to right) from the front of the press toward the rear in the direction of clockwise motion of plunger cam 7, and this curvature co-acts with said cam to effect the downward plunge of 18. A vertical longitudinal adjustment of plunger and bumper rod is provided (Figs. 1 and 2) so that for any given die 31 and punch 30 (Fig. 1) in chuck 28 screwed tight in the lower end of plunger 18, such punch will reach its operating position (as shown in Fig. 1) adjacent the die 31, at the instant plunger cam 7 reaches its lowermost position. This adjusting means is shown (Fig. 2) at the lower end of bumper shank 20 near the lower part of hole 26 in plunger 18, and by use of this means the distance may be varied between the top of mushroom head 22^A and the lower end of punch 30. This adjustment is executed with cam 7 in its lowermost position (Fig. 1) and such execution consists in operating the adjusting means so as to force plunger 18 down so as to carry punch 30 (Fig. 1) down to its operating position adjacent die 31. The adjusting means shown comprises (Fig. 2) a key 23 entering a hole 25 in plunger 18, the key entering also an angular dove-tail slot 21 in the lower end of bumper shank

20, near the bottom of circular hole 26 in bumper 18. Bumper-shank 20 fits tightly in circular hole 26 but not so tightly as to prevent adjustment by driving the key 23 in or out. Key 23 is formed with an angle 70 as shown so that the driving of the key inward will force plunger 18 downward. The latter movement of plunger 18 is not very great but in the prior construction of machines it resulted in a clearance space (as 75 shown at Z in Fig. 2) between the bottom of mushroom head 22^A and the end portion 29^A of plunger 18. Such clearance has amounted to several sixteenths of an inch 80 in some cases when the full range of adjustment has been used as it frequently the case. Of course, however, when key 23 is at the other extreme position of adjustment the bumper head 22^A will rest directly on 29^A, but this is not the usual condition, 85 and usually there is a substantial clearance as indicated at Z Fig. 2. Obviously it is desirable to start adjusting the tools with the key full out and no clearance opening at the top and lightly tap the key to drive 90 it in as may be necessary to obtain the correct adjustment between the punch and the die.

The effect of the repeated action of plunger-cam 7 on the square mushroom head 95 22^A of the above bumper-and-plunger construction of Fig. 2 (involving said clearance space Z) has been to bend the bumper shank 20 in the direction of cam rotation and to enlarge hole 26 in plunger 18, so 100 that the head 22^A became offset; and occasionally the effect has been to fracture bumper-shank 20; and the greater the clearance Z the greater were these results. The above have been very serious faults in these 105 machines which in all other respects have been built for long service without the use of repair or replacement parts.

In another application filed of even date herewith I have provided a remedy for the 110 above defect which consists of fundamental changes in the construction of both the plunger 18 and the bumper head 22^A. That construction is best adapted for use in manufacturing new eyelet machines.

In the present invention I have provided a remedy for the above defect which is included in the construction of Fig. 1 and this is particularly adapted to be added to eyelet machines already in use and provided 115 with the old general form of construction of bumper head and plunger head shown in both Figs. 1 and 2, save that in this invention the bumper head is made shorter than heretofore which may be easily done 120 on existing machines. In the present case the only change in the construction of bumper and the plunger 18 is such shortening of the vertical length of the bumper head 22^A as is shown by 22^C in Fig. 1 as 125 130

compared with the prior bumper head 22^a as shown in Fig. 2, this for a reason to be described.

Following is a description of the construction of Fig. 1 including the novel features.

At 32 in Fig. 1 (middle right) is a supporting member (shown in detail in Figs. 6 and 7) which has a hole 39 (Fig. 7) of about the same diameter as lifter rod 11, so that support 32 can be slipped on rod 11, to which it is then secured at the proper point by a pin 33 or the like. Member 32 is a support for the buffer 36 to be described. One end of support 32 has a rounded seat 34 formed in it (Figs. 7 and 3) and this seat has a bell mouthed opening 35 (Figs. 6, 7 and 1) on the side of support 32 toward bumper head 22 C (Fig. 1). Rounded seat 34 receives rounded end 37 (Figs. 3, 4 and 20 5) of a relief arm or buffer rod or plate 36, the rounded end 37 being inserted into seat 34 from the open end of support 32 (Fig. 7) to constitute a hinged connection. Buffer rod 36 has a relatively narrow neck 38 (Figs. 25 4 and 5) which extends through bell mouth 35 (Figs. 6 and 1). Buffer support 32 is fixed on lifter rod 11 at a point (Fig. 1) which permits buffer 36 to extend forward in a generally horizontal position toward 30 the front of the machine and rest on top of bumper head 22 C. Buffer 36 in its main part which rests on the bumper head 22 C has considerable horizontal area (Figs. 3 and 4). Fig. 3 shows three of these buffers 35 36 with their support 32 on the lifter rod 11, all arranged in series for three consecutive presses of an eyelet machine.

The relief arm or buffer 36 take the side sweep of the pushdown cam 7 so that the bumper head 22 C receives only the vertical component of the force which is transmitted to it from the cam via the buffer 36. The bumper head 22 C is thereby entirely relieved of the application of forces which 45 would tend to move it transversely and bend bumper shank 20 or enlarge shank hole 26. The thickness of the buffer plate 36 may be conveniently approximately one half its width so that it is substantial enough to be 50 so rigid as to transmit the transverse forces away from the bumper head 22 C and toward buffer support 32 which in respect of such forces is resisted by the entire structure including lifter rod 11 and its supports 55 including the main frame 1. The result is to confine and limit substantially all the operating power of the pushdown cam 7 to its intended object of moving the bumper and plunger in a right line as shown. The supporting of the buffer 36 independent of the bumper head 22 C (by means of member 32) leaves the buffer 36 free to take the strains as above stated.

With the construction of buffer support 60 32 above described including the hinged

seat for the buffer 36, the latter can always rest directly on the bumper head 22 C for any adjustment of bumper and plunger. Also on account of the interposition of buffer 36 between the pushdown cam 7 and bumper head 22^a, the height of the latter is reduced as shown, as compared with the prior bumper head 22^a of Fig. 2. That is, the height of an old bumper head 22^a (Fig. 2) is reduced to that of 22^a, Fig. 1, that is, 70 to an extent equal to the thickness of buffer 36, so as to provide space to receive buffer 36 between pushdown cam 7 and head 22^a. In adapting an old machine to the invention, the height of this head 22^a (Fig. 2) may be 75 reduced without great expense to that of 22^a, Fig. 1.

The use of this invention has demonstrated that it relieves the bumper shank 20 and plunger hole 26 from their liability to 80 be bent and enlarged respectively as described above.

The construction details of the assembly of Fig. 1 are as follows in addition to those already described.

Plunger 18 is held in frame 1 by front caps 15. Angle 17 (which unites plunger 18 to lifter rod 11) is properly located and held fast to lifter rod 11 by means of a pin, bolt or other fastening 16; and the angle 95 17 is fastened to plunger 18 by screws 19. A recess 27 is cut in the square plunger 18 to receive the uniting angle 17.

Lifter 9 (beneath which lifting cam 8 engages to lift up the plunger 18 and lifter 100 rod 11) is clamped fast to lifter rod 11 by having its rear end (right Fig. 1) slotted and the two parts engaged by screw 10.

Stability is given to the system consisting of the plunger 18, the bumper shank 20 and 105 lifter rod 11 by means of the adjustable spring compression friction 12 shown as embracing the upper part of the lifter rod 11 (top Fig. 1). This comprises the split bushing 12, the parts of which are held together around rod 11 by means of the springs shown. Bushing 12 is mounted in plate 13 secured fast to top of frame 1 as shown.

When the machine comprises more than a 115 few presses operated by a row of cams on shaft 2, a saddle 4 is secured by bolts 5 to the frame 1 at a point (not shown) intermediate the end bearing on shaft 2. The lower side of saddle 4 is conformed to receive a 120 collar 6 mounted in shaft 2 to rotate against a rounded-out lower surface of saddle 4 and thereby maintain correct alinement of cam shaft 2 against the action of the pushdown cams on the buffers 36.

125

I claim:—

1. In a machine of the character described, the combination with the pushdown cam and the relatively longitudinally adjustable plunger and bumper, the bumper having a 130

head located above the plunger and below the cam; of a buffer interposed between the cam and the bumper head; a support for the buffer; a lifter rod connected to move with the plunger; a lifting member and a lifting cam therefor, the lifting member and buffer being fixed to the lifter rod and whereby the buffer may engage on the top of the bumper head without being attached thereto; the buffer and its support having a loose joint to permit automatic compensation for adjustment of plunger and bumper.

2. In a machine of the character described and having an operating cam and a relatively longitudinally adjustable plunger and bumper, the bumper having a head located above the plunger and below the cam, the improvement consisting of a buffer interposed between the cam and the bumper head, said buffer being mounted to move with the plunger, whereby the buffer may engage on the top of the bumper head without being connected thereto, the buffer mounting being loose in the direction of compensation for the adjustment of plunger and bumper.

3. In a machine of the character described having an operating cam and a plunger and bumper, the bumper having a shank engaging a hole in the bumper and having a head lying beyond the plunger and larger than the bumper shank, the improvement consisting of a buffer engaging between the top of the bumper head and the operating cam but supported independently of the bumper head although traveling therewith.

4. In a machine of the character described, the construction for a buffer interposed between the operating cam and the bumper head said construction comprising a buffer plate, a support therefor having a vertical hole to receive its support in turn, the buffer plate having a cylindrical end connected to the plate by a neck, and the buffer support having a corresponding recess to receive said cylindrical end of the buffer and also having a bell-mouthed recess communicating with said cylindrical recess to receive the neck of the buffer plate and permit a limited freedom of movement of the plate; said cylindrical members having their axes horizontal whereby the pivotal movement of the buffer plate is along a line between the cam and the bumper head.

5. In a machine of the character described, the construction of a buffer between the operating cam and the bumper head which comprises a buffer plate and a support therefor constructed to travel with said buffer and give the plate a limited freedom of movement along the line between the bumper head and the cam but to hold the plate rigidly from movement transverse thereto.

6. In a machine of the character described, the construction for a buffer interposed between the operating cam and the bumper head said construction comprising a buffer plate adapted to be interposed between said cam and head, said plate having an extension constructed to be attached to a part of the machine other than the bumper head but arranged to travel therewith to which part the bumper is relatively adjustable, whereby the buffer plate may engage on the top of the bumper head without being connected thereto; said construction of the buffer plate extension permitting limited freedom of movement of the buffer plate along the line between the cam and bumper head but holding the buffer plate rigidly against movement transverse thereto.

7. In a machine of the character described, the construction for a buffer between the operating cam and the bumper head, said construction comprising a suitable support, other than the bumper head, a buffer plate adapted to be interposed between said cam and bumper head and having an extension constructed to be attached to said support, but arranged to travel therewith, whereby the buffer plate may engage on the top of the bumper head without being connected thereto.

8. In a machine of the character described, the construction for a buffer between the operating cam and the bumper head, said construction comprising a suitable support, other than the bumper head, a buffer plate of substantially uniform thickness adapted to be interposed between said cam and bumper head and having an extension constructed to be attached to said support, but arranged to travel therewith, whereby the buffer plate may engage on the top of the bumper head without being connected thereto.

WILLIAM D. PIERSON.
